FIG. 5.

FIG. 1.

FIG. 2.

FIG. 4.

FIG. 3.

FIG. 1 is a reduced scale perspective view of a cabinet for a security system showing my new design;

FIG. 2 is a top plan view thereof;

FIG. 3 is a right side elevational view thereof, the left side being a mirror image thereto;

FIG. 4 is a rear elevation view thereof; and

FIG. 5 is a front perspective view of another embodiment of my new design of FIG. 1 wherein the left end of the cabinet has been elongated, the right side being identical to that shown by FIG. 1 and the rear being substantially like FIG. 4 only elongated.

I claim:

The ornamental design for a cabinet for a security system, substantially as shown and described.
